UNITED STATES PATENT OFFICE.

JAMES J. GLEASON, OF STAMFORD, CONNECTICUT.

OIL BURNER.

Application filed May 16, 1925. Serial No. 30,691.

This invention relates to an oil burner of the aspiration type, and the broad object of the invention is to provide an oil burner of simplified and economic structure, which, at 5 the same time, will be much more efficient and reliable in use than oil burners of similar character heretofore known.

A more specific object is to provide an oil burner which will include in its structure 10 all of the attributes necessary to the burning of oil in ideal manner without necessity for employing in connection with the burner any additional power device or contrivance whatsoever of some class heretofore 15 ordinarily utilized to produce efficient combustion of ordinary commercial grades of fuel oil, the present burner being, in fact, a self-contained unit of construction adapted to care for clean and complete combustion 20 of fuel oil.

A further specific object is to provide an oil burner which can be automatically manipulated by means of a single valve, which valve will ordinarily be in the oil intake 25 pipe of the burner.

A further specific object is to provide an oil burner having means for superheating air before mixing it with oil to be burned, in order that said air can closely approximate 30 the flash point of the oil at the time of mixing.

A further specific object is to provide an oil burner having an arrangement for the aspiration of steam to the combustion chamber of the burner, whereby the efficiency of 35 the burner is greatly increased.

And a still further specific object is to provide an oil burner having a hot air oven or manifold adapted to receive primary air 40 to be heated to about the flash point of commercial fuel oil, a flash pan in proximity to said oven or manifold and adapted to serve as a dome for fuel oil to be burned, a combustion chamber where the burning of the fuel oil is accomplished, a water dispenser, an arrangement for admitting secondary air 45 to said combustion chamber, and a controlled oil intake leading to said dome or flash pan, the hot air oven or manifold being of relatively great capacity to insure 50 that more hot air than sufficient to afford complete combustion will be continuously aspirated to the combustion chamber, the heat of combustion being adapted to keep 55 the hot air oven or manifold heated to high

temperature, the heat of combustion also being adapted to heat water in the dispenser in order that steam is continuously present in the oil burner, the steam being adapted to be so situated as to travel to the combustion chamber or to be carried thereto by said secondary air, and the amount of fuel allowed to be fed to said dome or flash pan being adapted to control the working temperature of the oil burner.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and meant in no way in a limiting sense, changes in details of construction and arrangement of parts being 70 permissible so long as within the spirit of the invention and the scope of the appended claims.

In the accompanying drawings forming 80 a part of this specification,

Fig. 1 is a fragmentary elevational view disclosing an oil burner having the principles of the invention applied to use;

Fig. 2 is a vertical sectional view of the oil burner, the line upon which the section 85 is taken being more or less distorted to better bring out the construction;

Fig. 3 is a plan view with the oven or hot air manifold removed;

Fig. 4 is a sectional view as on line 4—4 90 in Fig. 2;

Fig. 5 is a fragmentary plan view better disclosing the relation of the component parts of the burner; and

Fig. 6 is a sectional view as on line 6—6 95 in Fig. 3.

With respect to Fig. 1 of the drawing, A represents a furnace, B the oil burner of the invention applied to use in the furnace, C an oil intake pipe leading to the burner, D an oil over-flow pipe leading from the burner, E mechanism of commerce (forming no part of the invention) for automatically shutting off the oil supply to the burner when there has been a predetermined 100 amount of oil to pass through the over-flow pipe, F is a water pipe leading to the burner, and G is mechanism of commerce used for keeping the water in the burner at a constant, predetermined level. The oil 110

burner can, of course, be applied to a variety of uses other than the use suggested in Fig. 1.

Of the improved oil burner, 10 denotes a base or frame, which may be a casting, including a hollow cylindrical section 11, vertical as disclosed, and a horizontally disposed top section 12. The top section 12 has a central, preferably cylindrical air duct 13, and adjacent said air duct said top section is dished to provide an annular cavity 14 encircling said air duct and adapted to receive, in a manner to be explained, oil which may enter the burner when not lighted.

The top section 12 has upstanding vanes which are desirably of spiral formation and are spaced at equal distances apart about said top section, all of said vanes extending outwardly from locations adjacent the air duct of the top section and preferably terminating at or adjacent to the margin thereof. As disclosed, alternate vanes 15 are solid, and alternate vanes 16 are hollow, numeral 17 representing vertical air passages or ducts through said vanes 16 and through the top section, which air passages or ducts, naturally, lead from the space, denoted 18, within the hollow cylindrical section 12.

The section 11 of the base or frame may rest upon a grate 19, and may be surrounded by suitable material 20, which may be some refractory material, enveloping the lower portion of said section 11. The hollow or cylindrical section 11 constitutes a manifold for atmospheric air drawn into the oil burner in a manner which will become obvious.

Numeral 21 denotes a water pan or dispenser bolted as at 22 to the underside of the top section 12 of the base or frame and provided with a water inlet 23 at the inner end of the water pipe F. The water pan or dispenser has a central cylindrical duct 24 which is, as shown, in vertical alignment with the air duct 13 of the top section 12, and the upper end of this air duct 24 terminates at a location spaced a slight distance from the dished portion of the top section, whereby there can be communication through a space 25 between the water pan or dispenser and said air duct 13.

Numeral 26 indicates spaced apart evaporator radiators, which may be integral with the casting comprising the base or frame 10, extending downwardly from the top section 12 of said base or frame and entering the water pan or dispenser. As disclosed, the water pan or dispenser has compartments 27 each conforming generally to the shape of the evaporator radiators, there being a radiator for each compartment. The arrangement here is such that the radiators can come into intimate contact with water in the dispenser when immersed to the level desired. The mechanism G of commerce

keeps the water in the dispenser at a constant level, and, consequently, the radiators are always immersed in the water to a constant depth, which depth may be that most suitable to obtain the water vaporizing result desired, as will be understood.

Numeral 28 represents a hot air oven or manifold which is situated upon the vanes 15 and 16 of the oil burner (see Fig. 2). This manifold 28 has openings 29 which allow communication between the air ducts or passages 17 of the vanes 16 and the interior of the hot air oven or manifold, and said manifold 28 also has a central cylindrical downwardly disposed air duct 30 which is above and desirably in alignment with the air duct 13 of the top section 12. The locations, denoted 31, where the vanes 16 engage the hot air oven or manifold will be properly reinforced to provide suitable connections insuring against leaks.

Numeral 32 denotes a dome or flash pan, preferably circular and crowned (about the construction disclosed), which is situated between the air ducts 13 and 30, spaced a desired and predetermined distance from each duct. As shown, this dome or flash pan rests upon three steps 33 of certain of the vanes 15, although it could be supported in some other suitable manner. 34 represents the inner end portion of the oil intake pipe C, which inner end portion extends through the ducts 13 and 24 of the top section 12 and the water dispenser, respectively, and is threaded into the center of the dome or flash pan in such manner that oil from the intake pipe can be fed to the upper surface of said dome or flash pan, as will be clear from Fig. 2. 35 is the inner end of the overflow pipe D which communicates with the cavity 14 to remove therefrom oil which may enter the burner when not lighted. 36 is a valve of any suitable construction located in the oil intake pipe C and adapted to control the flow of oil to the dome or flash pan.

The hot air oven or manifold 28 and the top section 12 of the base or frame 10 are adapted to together provide a combustion chamber 37 at the center of which the dome or flash pan 32 is situated, and the vanes 15, 16 divide the portion of said combustion chamber surrounding said dome or flash pan into a plurality of separate compartments, which are, in fact, spiral passages leading from the location of the dome or flash pan approximately to the margin of the oil burner, and there opening to the atmosphere. It will be evident that a greater or less number of vanes 15, 16, and 27 constructed in a manner different from that illustrated, could be utilized.

The manner in which the oil burner functions in use is as follows: The valve 36 is moved to open position when fuel oil is to

be fed to the upper surface of the dome or flash pan 32, and a flame is applied to the oil at the dome or flash pan. As the oil burns, primary air passing upwardly in the direction of the arrows X, through the space 18 of the atmospheric-air-manifold or section 11, and through the heated air ducts or passages 17 of the hollow vanes 16 to the oven or manifold 28, feeds the flames via the air duct 30, and secondary air passing upwardly, in the direction of the arrows Y, through the space 18 and through the air ducts 24 and 13, feeds said flame via space 38 between the air duct 13 and the dome or flash pan 32. Almost immediately the oven or manifold 28 becomes heated to a high temperature, and said oven is desirably of relatively great capacity to insure that it will continuously contain more than sufficient superheated air to afford complete combustion of oil fed to the combustion chamber. Preferably, the temperature of air at the interior of the hot air oven or manifold 28 approximates the flash point of the grade of fuel oil being burned. The actual or working temperature of said hot air oven or manifold will vary according to the amount of oil allowed to be fed past the valve 36 to the dome or flash pan to be burned, as will be evident. The spiral passages provided by the vanes 15 and 16 and leading from the dome or flash pan will receive the burning gases from the space of the combustion chamber in proximity to the dome or flash pan, and in these passages the combustion of the oil will be completed. The rapid passage of the completely burned gases out of said spiral passages of the combustion chamber will cause air to be rapidly aspirated to the space in proximity to the dome or flash pan and within the central part of the combustion chamber. The major portion of this air (primary air) will be drawn in through the hot passages 17 and fed to the flame from the hot air oven or manifold, but some air (secondary air) will enter via the air ducts 24 and 13 and the space 38.

The evaporator radiators 26 are, as disclosed, in close proximity to the lower wall of the combustion chamber 37, and are preferably not far distant from the vanes 15 and 16, so that heat is absorbed by the radiators and imparted to water in the pan or dispenser 21 to cause steam to be present in the upper portion of said pan or dispenser at all times while the oil burner is operative. The only place for this steam to escape is through the space 25. Naturally, air (secondary air) aspirated to the combustion chamber via the air ducts 24 and 13 and the space 38, carries steam along with it, and, itself intimately mixing with the burning gases in the combustion chamber, causes the steam and burning gases to be thor-

oughly mixed, thus greatly increasing the efficiency of the oil burner.

Oil which may pass into the burner when not lighted will run from the dome or flash pan to the annular cavity 14 and thence out of the burner through the over-flow pipe D leading to the mechanism E.

What I claim is:

1. In an oil burner, an atmospheric-air-manifold including a hollow, vertical portion and a horizontal portion, there being a duct in said horizontal portion, a water dispenser in communication with said atmospheric-air-manifold, a hot air manifold above said atmospheric-air-manifold, vanes extending between said manifolds and providing, together with both manifolds, a combustion chamber, there being air passages through certain of said vanes and affording communication between said hot air manifold and said atmospheric-air-manifold, and said hot air manifold having a downwardly disposed duct affording communication between said combustion chamber and hot air manifold, a flash pan in said combustion chamber adjacent said hot-air-manifold-duct for receiving oil to be burned, and means whereby the feed of oil to said combustion chamber can be controlled.

2. The combination as specified in claim 1, and the water dispenser being within said atmospheric air manifold and having a duct, there being a space between said water dispenser and said duct in said horizontal portion, and evaporator radiators in proximity to said combustion chamber and adapted to enter water in said dispenser, there being a space between said flash pan and the duct in said horizontal portion whereby air carried to said combustion chamber via said water dispenser duct and said horizontal portion duct will carry steam to said chamber.

3. The combination as specified in claim 1, the water dispenser being within said atmospheric-air-manifold and including evaporator radiators integral with said horizontal portion.

4. The combination as specified in claim 1, wherein the combustion chamber has a central portion in which the flash pan is arranged and the vanes provide spiral passages leading from said central portion to the atmosphere.

5. In an oil burner, an atmospheric-air-manifold including a hollow, vertical portion and a horizontal portion, there being a duct in said horizontal portion, a hot air manifold above said atmospheric-air-manifold, vanes extending between said manifolds and providing, together with both manifolds, a combustion chamber, there being air passages through certain of said vanes and affording communication between said hot air manifold and said atmospheric-air-manifold, and said hot air manifold hav-

ing a downwardly disposed duct affording communication between said combustion chamber and hot air manifold, a flash pan in said combustion chamber adjacent said 5 hot-air-manifold duct for receiving oil to be burned, the combustion chamber having a central portion in which the flash pan is arranged and the vanes provide spiral pas-

sages leading from said central portion to the atmosphere, and means whereby the feed 10 of oil to said combustion chamber can be controlled.

Signed at Stamford, in the county of Fairfield, and State of Connecticut, this 11th day of May, A. D. 1925.

JAMES J. GLEASON.
